(57) CLAIM

The ornamental design for a candle with gift box, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a candle with gift box, illustrating an outer box of the candle with gift box;

FIG. 2 is a right side elevation view thereof;

FIG. 3 is a left side elevation view thereof;

FIG. 4 is a rear elevation view thereof;

FIG. 5 is a perspective view of an inner packaging with a candle inside, once the outer box of the candle giftset has been removed;

FIG. 6 is a top plan view of the candle;

FIG. 7 is a bottom perspective view of the front of the candle;

FIG. 8 is a left side view of the candle;

FIG. 9 is a right side view of the candle;

FIG. 10 is a front elevation view of the inner packaging;

FIG. 11 is a rear elevation view thereof;

FIG. 12 is a right side elevation view thereof, and,

FIG. 13 is a left side elevation view thereof.

All surfaces not shown form no part of the claimed design.
